The ornamental design for a stained glass crown for torchère lamp shade, as shown and described.

DESCRIPTION

FIG. 1 is a top perspective view of the stained glass crown for a torchère lamp shade showing our new design;

FIG. 2 is a top plan view thereof on a reduced scale, the bottom plan view being identical; and,

FIG. 3 is a side elevational view thereof, all sides being identical.

The glass panels are shaded to indicate translucency.
